UNITED STATES PATENT OFFICE.

ALFRED CAREY LEASURE, OF ALVIN, COLORADO.

THILL-COUPING.

1,176,376.

Specification of Letters Patent. Patented Mar. 21, 1916.

Application filed September 11, 1915. Serial No. 50,130.

To all whom it may concern:

Be it known that I, ALFRED CAREY LEASURE, a citizen of the United States, residing at Alvin, in the county of Yuma and State of Colorado, have invented certain new and useful Improvements in Thill-Couplings, of which the following is a specification, reference being had to the accompanying drawings.

10 This invention relates to improvements in thill couplings, and an object thereof is the provision of a thill coupling in which a spring is provided to bear against the thill iron, to prevent rattling of the same in the 15 shackles of the coupling clip.

A further object of this invention is the provision of a thill coupling in which a spring is provided, the spring performing the double function of preventing rattling 20 of the thill, and also forming a locking device for preventing accidental disengagement of the coupling bolt from the device.

With these and other objects in view, my invention consists in the novel construction, 25 combination, and arrangement of parts to be hereinafter more fully described, claimed, and illustrated in the accompanying drawing, in which—

Figure 1 is a view partly in side elevation and partly in section illustrating a thill coupling constructed in accordance with an embodiment of my invention. Fig. 2 is a top plan view of the device as disclosed in Fig. 1; and Fig. 3 is a rear elevational view of 35 the device as herein set forth.

Referring more particularly to the drawing, the numeral 1 designates the front axle of a vehicle to which the usual clip 2 is connected, the clip being provided with the 40 threaded legs 3 which receive the fastening plate 4, the plate being secured against the under face of the axle by the nuts 5. The clip is provided with a pair of forwardly extending transversely apertured shackles 6, 45 which receive therebetween the eye of a thill iron 7, and one of the legs of a U-shaped coupling bolt 8 is passed through the apertures in the shackles and the eye of the thill iron to pivotally connect the thill iron to the 50 axle.

A flat spring 9 is provided, the spring being bent upon itself at one end to form a loop 10, the loop being engaged below the inner end of the thill iron to bear against 55 the same, the body portion of the spring and the backwardly bent end thereof ex-

tending upwardly between the thill iron and the body of the clip between the shackles thereof, the opposite end of the spring extending across the clip directly above the 60 same. The other leg of the bolt is disposed between the body portion of the spring and the backwardly bent end thereof, the last mentioned leg being provided with an annular recess 11 adjacent its end, the reduced 65 portion being of substantially the same length as the width of the spring plate, so that the spring and the backwardly bent portion thereof engage in the reduced portion of the leg to prevent accidental disengagement of the bolt from the shackles of 70 the clip and the eye of the thill iron. A lever 12 is provided, one end of the lever having offset flanges 13 formed on its opposite edges, each of the flanges being formed 75 with a plurality of openings 14, the openings in the flanges being disposed in transverse alignment, and mounted in the outermost pair of the openings is a pivot pin 15 to which the free end of the spring is pivotally connected. The opposite ends of a U-shaped link 16 are mounted in one pair of the openings inwardly of the pivot pin, the intermediate portion of the U-shaped link being engaged with the nut 5 which secures 80 the rear end of the plate 4 to the axle. 85

In the practical use of my device, when it is desired to connect a thill iron to the coupling, the lever 12 is in open position, and the eye of the thill iron is disposed between 90 the shackles 6 of the clip so that the eye registers with the openings in the shackles. When the eye is in this position, the U-shaped bolt is positioned so that one leg thereof passes through the apertured shackles and 95 the eye and so that the other leg of the U-shaped bolt is disposed between the backwardly bent end of the spring and the body portion thereof in a position so that the spring and backwardly bent end thereof engage in the reduced portion of the bolt. The lever 12 is then swung so that the same rests upon the spring above the axle, and in 100 swinging the lever to its locked position, it will be seen that the looped portion of the 105 spring is drawn upwardly to tightly engage the eye of the thill iron to prevent rattling of the same and that the spring and backwardly bent end thereof are tightly engaged in the reduced portion of the bolt so that 110 accidental disengagement of the bolt from the shackles is prevented. It will be seen

that the looped portion of the spring will prevent moving of the spring upwardly between the eye of the thill iron and the body portion of the clip. When it is desired to 5 remove the thill iron from the clip, upon moving the locking lever to open position, the link 16 may be readily disengaged from the nut 5, so as to loosen the engagement of the spring from the reduced portion of the 10 bolt, whereby the same may be quickly moved from engagement with the shackles and the eye.

Having thus fully described my invention, what I desire to secure and claim by 15 Letters Patent is:—

A thill coupling comprising a clip for attachment to an axle, said clip being provided with spaced shackles, a thill iron having an eye formed thereon and disposed between said shackles, a U-shaped locking bolt having one leg thereof disposed through said shackles and the eye of the thill iron, a curved spring engaged over the top of the clip and having one end thereof returned 20 upon itself to form a loop, said loop being 25

disposed between the shackles of the clip to bear against the under portion of the eye of the thill iron, a lever pivotally connected to the opposite end of the spring, and a link connected to the lever for engagement with one of the ends of the clip, the other leg of the locking bolt being positioned against the clip above the shackles and between the intermediate portion of the spring, and the free end portion of the returned part of the 30 spring, the intermediate portion of the spring being above the second leg of the bolt and the returned part of the spring being below said leg, said second leg being provided with an annular recess to receive 35 the intermediate portion of the spring and the returned part thereof, whereby the bolt is held against longitudinal movement.

In testimony whereof I hereunto affix my signature in the presence of two witnesses. 40

ALFRED CAREY LEASURE.
